UNITED STATES PATENT OFFICE.

SHELLEY W. FORD, OF CHICAGO, ILLINOIS, ASSIGNOR OF ONE-HALF TO RICHARD A. SUNDVAHL, OF CHICAGO, ILLINOIS.

TRousERS STRETCHER AND HANGER.

1,296,942.

Specification of Letters Patent. Patented Mar. 11, 1919.

Application filed September 4, 1917. Serial No. 189,453.

To all whom it may concern:

Be it known that I, SHELLEY W. FORD, a citizen of the United States, and a resident of Chicago, county of Cook, and State of Illinois, have invented certain new and useful Improvements in Trousers Stretchers and Hangers, of which the following is a specification.

The invention seeks to provide an improved trousers stretcher and hanger of simple construction which can be readily applied to trousers of different sizes to effectively stretch the same. A further object of the invention is to provide a trousers stretcher and hanger which can be compactly folded.

The invention consists in the features of improvement hereinafter set forth, illustrated in the preferred form in the accompanying drawings and more particularly 20 pointed out in the appended claims.

In the drawings, Figure 1 is a view in elevation of the improved trousers stretcher and hanger with the parts in position for use. Fig. 2 is an edge view thereof. Fig. 3 is a view showing the improved trousers stretcher and hanger in folded condition. Fig. 4 is an enlarged detail view in section on the line 4—4 of Fig. 1.

The improved trousers stretcher and 30 hanger comprises a longitudinal bar or member 10, a pair of stretcher bars 11 pivotally and adjustably connected at their inner ends to the lower ends of the bar 10 and having clamps at their outer ends for engaging the upper portions of the trousers and a transverse clamp at the upper end of the longitudinal member for gripping the lower ends of the trousers legs.

The bars or members 10 and 11 are in the 40 form of thin flat strips and are preferably made of wood. The transverse clamp at the upper end of the device is also preferably made of wood and preferably comprises two thin flat members 12 and 13 which are adjustably connected by a pair of bolts 14 having clamping wing nuts 15 thereon. The 45 transverse clamp is triangular in outline and is connected to the upper end of the longitudinal bar or member 10 preferably by 50 means of a pivot bolt 16 which extends through the central portion of the clamp member 12 adjacent its lower edge. The lower central portion of the other clamp member 13 is cut away so that the rounded 55 head of the pivot bolt 16 will not mar the

lower ends of the trousers when gripped between the two members. One clamp member, in the form shown the member 12, is provided with a suspension hook 17 fixed at its lower end to the upper central portion of 60 the clamping member.

The parts 11 are, as stated, pivotally and adjustably connected to the lower end of the bar or member 10. For this purpose, the lower end of the bar 10 is provided with a 65 longitudinal slot 18 and a pivot bolt 19 extends through the ends of the bars 11 and the slot 18 and is provided with a clamping wing nut 20. Preferably, as shown, the inner ends of the bars 11 are arranged on opposite 70 sides of the lower end of the bar 10. The outer ends of the bars 11 are provided with short clamping pieces 21 adjustably connected thereto by bolts 22 having wing nuts 23 thereon. In operation the lower ends of 75 the trousers legs are gripped between the clamp members 12 and 13 and the upper portions of the trousers are gripped between the lower ends of the stretcher bars 11 and the clamp members 21 thereon. In order to 80 effectively grip the upper and lower portions of the trousers without injuring the fabric thereof, the outer ends of the clamp members 12 and 13, the inner ends of the 85 clamp members 21 and the portions of the bars 11 associated with the latter clamps are provided with facing strips 24 of felt or the like. Preferably also, thin spacing blocks 90 25 and 26 substantially equal in thickness to a pair of trousers when in position on the stretcher, are interposed between the clamp members. The block 25 is interposed between the central portions of the clamping members 12 and 13 and is fixed to the clamp member 12, and the blocks 26 are interposed 95 between the outer ends of the bars 11 and clamping strips 21 and are fixed to bars 11.

The clamping members are forced into snug engagement with the trousers by means of the wing nuts 15 and 23 on the 100 clamp bolts 14 and 22. By loosening the nut 20 on the clamping pivot bolt 19, the stretcher bars can be easily adjusted and the clamp members 21 thereon readily engaged with the upper portions of the trousers of 105 different length and width. When the clamps are properly engaged with the upper and lower portions of the trousers, the inner ends of the stretcher bars 11 and the bolt 19 are forced toward the lower end of 110

the longitudinal bar 10. When this is done, the outer ends of the stretcher bars 11 not only move in lengthwise direction but also swing outwardly about the pivot bolt 19 so that the fabric of the trousers is stretched or placed under tension both in a longitudinal and a transverse direction. When the desired tension is placed upon the trousers by adjusting the stretcher bars 11, the nut 10 on the bolt 19 is tightened to secure the bars in adjusted position. The parts are shown in position for use, in Figs. 1 and 2, the trousers being indicated in dotted lines in Fig. 1. When not in use, the parts can be compactly folded by swinging the transverse clamp and suspension hook at the upper end of the device through a half turn about the pivot bolt 16 and by swinging the stretcher bars in opposite directions about the pivot bolt 19 into positions adjacent and substantially parallel with the bar 10. This folded position of the device is shown in Fig. 3.

Changes may be made in the details set forth without departing from the essentials of the invention as defined in the claims.

I claim as my invention:

1. A trousers stretcher comprising a longitudinal bar, a transverse clamp at the upper end of said longitudinal bar for gripping the lower ends of the trousers legs, a pair of stretcher bars having clamps at their outer ends for gripping the upper portions of the trousers, and a combined pivotally and longitudinally adjustable connection between the inner ends of both of said stretcher bars and the lower end of said longitudinal bar, said connection having means for clamping both of said stretcher bars in different angular and longitudinally adjusted positions with respect to said longitudinal bar, substantially as described.

2. A trousers stretcher comprising a longitudinal bar, a rigid transverse clamp member centrally connected to the upper end of said longitudinal bar and having means for gripping the lower ends of the trousers legs, a pair of stretcher bars having clamps at their outer ends for gripping the upper portions of the trousers, and a combined pivotally and longitudinally adjustable connection between the inner ends of both of said stretcher bars and the lower end of said lon-

gitudinal bar, said stretcher bars being of substantially the same length as said longitudinal bar and being foldable into substantially parallel relation therewith and said stretcher bars being downwardly and outwardly inclined in operative position, said adjustable connection having means for clamping said stretcher bars in different angular and longitudinally adjusted positions with respect to said longitudinal bar, substantially as described. 55

3. A trousers stretcher and hanger comprising a longitudinal member, a rigid transverse clamp member having means for gripping the lower ends of the trousers legs centrally pivoted to the upper end of said member, a suspension hook fixed to said clamp member, and a pair of foldable stretcher bars having pivotally and longitudinally adjustable connections at their inner ends with the lower end of said longitudinal member and having clamps at their outer ends for engaging the upper portions of the trousers, substantially as described. 65

4. A trousers stretcher and hanger comprising a longitudinal bar, a transverse clamp at the upper end of said longitudinal bar for gripping the lower ends of the trousers legs, a pair of stretcher bars having clamps at their outer ends for gripping the upper portion of the trousers, said bars being formed of thin, flat strips and said longitudinal bar having a slot in its lower end extending lengthwise thereof, and a clamping pivot-bolt extending through the inner ends of said stretcher bars and said slot, substantially as described. 70

5. A trousers stretcher and hanger comprising a longitudinal member, a rigid transverse member centrally pivoted at the upper end of said longitudinal member, a pair of stretcher members both having pivotally and longitudinally adjustable connections with the lower end of said longitudinal member, said members and said bars being formed of thin flat strips, thin flat gripping members adjustably connected to 85 said transverse member and to the outer ends of said stretcher members and a suspension hook fixed to said transverse member, substantially as described. 90

SHELLEY W. FORD.
